UNITED STATES PATENT OFFICE.

THEODORE W. FOSTER, OF PROVIDENCE, RHODE ISLAND.

DESIGN FOR A COVER FOR PUFF-BOXES OR SIMILAR ARTICLES.

SPECIFICATION forming part of Design No. 33,237, dated September 25, 1900.

Application filed August 24, 1900. Serial No. 27,954. Term of patent 7 years.

To all whom it may concern:

Be it known that I, THEODORE W. FOSTER, a citizen of the United States, residing at Providence, in the county of Providence and State of Rhode Island, have invented and produced a new and original Design for the Cover of a Puff-Box or Similar Article, of which the following is a specification, reference being had to the accompanying drawings, forming part thereof.

Figure 1 is a top view of a cover for puff-boxes and similar articles, showing my design. Fig. 2 is a transverse section on the line X X of Fig. 1.

As shown in the drawings, the leading or material feature of my design consists of the central convex panel surrounded by a circular ornamental border in which are a series of bold foliated scrolls having a rose ornament extending over part of the central panel on one side and the foliation of a radially-disposed scroll extending over part of the raised central panel on the opposite side. From the stem of the rose ornament bold foliated scrolls

having their ends curved inward form a circular border, the outer lines of which follow the circular margin of the cover, while the inwardly-curved scrolls and foliations approach and partly extend over portions of the central panel. The rose ornament extends over part of the central panel, and a radially-disposed foliated scroll supporting a fruit-and-flower ornament has the foliation of the scroll extending over part of the central panel opposite the rose ornament.

Having thus described my invention, what I claim as new, and desire to secure by Letters Patent, is—

The design for the cover of a puff-box or similar article as herein shown and described.

In testimony whereof I have signed my name to this specification in the presence of two subscribing witnesses.

THEODORE W. FOSTER.
